Henry McGann

UNITED STATES PATENT OFFICE.

HENRY McGANN, OF CLEVELAND, OHIO.

IMPROVEMENT IN PAPER-REELS FOR TELEGRAPHS.

Specification forming part of Letters Patent No. 41,312, dated January 19, 1864.

To all whom it may concern:

Be it known that I, HENRY McGANN, of Cleveland, in the county of Cuyahoga and State of Ohio, have invented new and useful Improvements in Telegraph-Paper-Reel Machines; and I do hereby declare that the following is a full and complete description of the construction and operation of the same, reference being had to the accompanying drawings, making part of this specification, in which—

Figure 1 is a side view, and Fig. 2 is an end view in the direction of the lines *x x* in Fig. 1.

Like letters refer to like parts.

A platform, A, forms the foundation upon which the machine rests. At each end of this is a standard, B. The table C is supported by the standards B.

The reel is represented at D, and is constructed in the usual manner, with radial arms upon each end, leaving a space between wide enough for the ribbon of paper. This reel can be readily taken off and put on its axle by removing the pin *d*. The reel D is supported by the standard E, which is secured to the platform A. Another reel, F, which receives the paper from the reel D, is supported, in a manner similar to that before described, by the standards G, which standards also support the gearing which gives motion to the reel. The reel F is caused to revolve by means of gearing *J J'* and the weight H, which is attached to the cord I. This cord passes over the pulley L and fastens to the pulley or gear shaft

H'. A pawl and ratchet (shown at *b*) allow the weighted cord I to be wound up without turning the reel. When the reel F is full, the paper being entirely wound off from the reel D, the reels can be changed, so that the full reel will be upon the standard E. In this way the same piece of paper can be used a number of times by a slight adjustment of the telegraphic instrument. The paper *a* passes from the full reel upon the standard E, through an opening in the table C, through the recording instrument, and down through another opening to the reel F, in the direction of the arrow.

The telegraphic instrument is placed upon the table C in such position that the paper *a* passes through it in receiving the impressions as communications are being made. The tension on the paper by the weight as it passes onto the receiving-reel is not so great but that it can be easily drawn back, in order to read the message, as is sometimes required.

What I claim as my improvement, and desire to secure by Letters Patent, is—

The herein-described arrangement of the mutually-exchangeable reels D and F, in combination with the gears *J J'*, cord I, pulley L, and weight H, the several parts being constructed, arranged, and operating as and for the purpose herein set forth.

HENRY McGANN.
